(57) **CLAIM**

The ornamental design for an oil rack stand, as shown and described.

DESCRIPTION

FIG. 1 is an oblique view of an oil rack stand according to the present application.

FIG. 2 is a front view of the oil rack stand of FIG. 1.

FIG. 3 is a rear view of the oil rack stand of FIG. 1.

FIG. 4 is a right view of the oil rack stand of FIG. 1.

FIG. 5 is a left view of the oil rack stand of FIG. 1.

FIG. 6 is a top view of the oil rack stand of FIG. 1; and, FIG. 7 is a bottom view of the oil rack stand of FIG. 1.

The broken lines are included for the purpose of illustrating environmental structure and form no part of the claimed design.
